GAS-BURNING APPARATUS.

1,256,301.

Specification of Letters Patent. Patented Feb. 12, 1918.

Application filed May 8, 1912, Serial No. 695,925. Renewed June 28, 1917. Serial No. 177,596.

To all whom it may concern:

Be it known that I, CARLETON ELLIS, a citizen of the United States, and resident of Montclair, Essex county, New Jersey, 5 have made certain new and useful Inventions Relating to Gas-Burning Apparatus, of which the following is a specification, taken in connection with the accompanying drawing, which forms part of the same.

10 This invention relates to apparatus for burning explosive gaseous mixtures which comprises a porous and permeable bed or diaphragm of refractory material into which the explosive gaseous mixture is fed so as 15 to burn at or near the outer surface of the bed or diaphragm and maintain said outer surface in a state of incandescence. The outer portion or surface layer of the diaphragm may be coated with or formed of 20 rare earth actinic material so as to promote the luminosity therof and make the apparatus thereby more effective for lighting purposes. The invention aims to provide apparatus of this character in which 25 the localization of the combustion within the desired portion of the diaphragm is maintained by preventing the inner portion of the diaphragm or bed from becoming too highly heated. For this purpose, the dia- 30 phrags or beds in accordance with the present invention are formed with cooling passages extending through the inner or rear portion thereof, through which pas- 35 sages a cooling fluid, which is most desirably the air to be used in forming the explosive mixture, is caused to pass. By caus- 40 ing the air used in forming the explosive mixture to pass through the cooling passages of the bed, the desired cooling of the bed is effected and at the same time a pre- 45 heating of the air used in the mixture is secured with resulting increase in heat at the combustion zone.

In the accompanying drawing showing 45 in a somewhat diagrammatic way several illustrative embodiments of this invention, Figure 1 is a vertical section of one form of apparatus.

Fig. 2 is an enlarged sectional detail showing a portion of the diaphragm; and

Fig. 3 is a section showing another form of apparatus.

This apparatus may be in the form of a portable convertible lamp and heater and 55 may be supplied with gas under the desired

pressure in any suitable way. As shown in Fig. 1, the casing 1 of iron or other suitable metal or material may have mounted therein the porous refractory diaphragm 2 formed of substantially uniform sized granules of 60 fire clay or other suitable refractory material which may conveniently be made coherent as by calcination after coating the granules with a relatively small proportion of suitable fluxing material. It is also de- 65 sirable to have the outer or surface layer 3 of the diaphragm formed of granules composed of or coated with suitable actinic material comprising such rare earth oxids as cerium, thorium, yttrium oxids or the 70 like which may be readily applied in the form of a coating to the outer layer or portion of the diaphragm, preferably before calcination of the molded diaphragm mate- 75 rial. In the form indicated in Fig. 1 the 75 diaphragm is also formed with suitable cooling passages in which suitable cooling air pipes 4 may be arranged if desired and these air pipes may be conveniently formed of thin wrought iron or the like and em- 80 bedded in the diaphragm material during the calcination process in which case the diaphragm may be mounted so as to bring these cooling pipes 4 into alignment with suitable apertures in the casing. If desired, 85 however, these cooling passages may be molded in the diaphragm material and pro- 90 vided with any suitable impervious lining such as an enamel, vitreous or fluxing coat- 95 ing which becomes impervious when the 90 diaphragm granules are united by calcina- 100 tion. The casing may be formed with a suitable chamber 5 which may be supplied with an explosive gaseous mixture in any desired way, as through the communicating 105 throat 6. A suitable injecting nozzle such as 7 may be mounted in any desired way in co-operation with this throat so as to inject the illuminating gas, coal gas or other suit- 110 able combustible gas or vapor into the throat at such pressure as to carry therethrough sufficient air to form an explosive mixture within the chamber containing substantially the proportions of air required for complete combustion. The air may be admitted to suitable openings such as 10 controlled by a rotary or other damper 11 regulating the amount of induced air so as to secure the desired explosive mixture when the gas valve 8 is turned on so as to allow gas sup-

plied through the flexible gas pipe 9, for instance, to be delivered from the injecting nozzle 7. In this way the gas preferably issuing under a pressure of a pound 5 or so can readily induce sufficient air to form the explosive mixture within the gas chamber and feed it forward through the highly porous diaphragm, a pressure in the chamber of a fraction of an inch of water being 10 sufficient for this purpose when the diaphragm granules are about a sixteenth of an inch in size. In order to more definitely localize the zone of surface combustion within the diaphragm air or other cooling 15 fluid may be allowed or caused to circulate through the cooling air pipes 4 and this may be conveniently accomplished by drawing through these pipes or passages part or all of the air used for combustion of the fuel 20 within the diaphragm. For this purpose a suitable shield such as 12, may be mounted on the casing so as to form a suitable air chamber 13 communicating with one end of the cooling pipes 4 so as to allow the air 25 therefrom to be drawn by the injecting jet into the throat and communicating gas chamber. In this way the inner portions of the diaphragm are more effectively cooled and the zone of intense surface combustion 30 more definitely located in the outer diaphragm layer.

Under normal conditions the explosive gaseous mixture burns with highly accelerated surface combustion within the outer 35 portion of the diaphragm, heating the granules to bright redness or incandescence so as to give considerable light in this way. If desired, however, this convertible burner may be supplied with a somewhat larger 40 amount of gas so that combustion largely occurs within the extreme outer layers of the diaphragm and to some slight extent in the form of blue flame combustion in the interstices of the outer layer so as to intensely 45 heat the exposed outer portion of the diaphragm and render highly luminous the surface granules coated with the rare earth actinic material used for this purpose. The cooling devices are of special utility under 50 these circumstances since they are of course preferably so disposed as to absorb from the inner portion of the diaphragm any excess of heat which tends to develop therein in case of any incipient creeping back of the 55 zone of combustion so that the combustion is definitely localized in the surface layer of the diaphragm where the maximum actinic effect is produced. It is of course understood that diaphragms of this character 60 may be mounted in any suitable way and as indicated the diaphragm is adjustably mounted on a suitable portable support, the bracket 14 on the casing having hinged connection with the standard 15 connected to 65 the base 16. By tightening the screw 17

the device may be rigidly held in position and may be angularly adjusted to the desired extent on loosening this screw. A simpler form of convertible apparatus is shown in Fig. 3 as comprising the casing 18 70 within which the diaphragm 2^a having a similar surface layer 3^a in which the particles are suitably coated with rare earth actinic material. The injecting pipe 19 may be connected in any desired way with the 75 casing and may be provided with the gas pipe 20 and air pipe 21 through which the air and gas may be forced under suitable pressure so as to mix and form the desired explosive mixture and inject the same into 80 the casing for intense surface combustion in the outer diaphragm layer. This injecting pipe may of course serve to support the casing and diaphragm at a suitable distance from the wall of a room, for instance. 85

Having described this invention in connection with a number of illustrative embodiments, forms, proportions, parts, materials and arrangements, to the details of which disclosure the invention is not of 90 course to be limited, what is claimed as new and what is desired to be secured by Letters Patent is set forth in the appended claims:

1. In heating and lighting apparatus, a casing, a porous refractory diaphragm 95 mounted in said casing and formed of united porous granules of substantially uniform size, the surface layer granules being coated with rare earth actinic material to promote their luminosity, cooling air pipes forming 100 cooling passages through said diaphragm, a gas chamber formed in said casing behind said diaphragm, a throat communicating with said gas chamber and with the outside air, an injecting gas nozzle coöperating with 105 said throat to inject a mixture of gas and induced air into the same and force the resulting explosive mixture through said diaphragm to burn within the surface layer thereof and maintain said coated granules 110 in incandescent highly luminous condition, a regulating damper to control the amount of induced outside air drawn in by said injecting nozzle, and an air chamber communicating with said cooling passages and with said 115 throat to allow said injecting nozzle to draw air therethrough and cool the inner portions of said diaphragm.

2. In heating and lighting apparatus, a casing, a porous refractory diaphragm 120 mounted in said casing and formed of united porous granules, the surface layer granules being coated with rare earth actinic material to promote their luminosity, cooling 125 passages through said diaphragm, a gas chamber formed in said casing behind said diaphragm, a throat communicating with said gas chamber, an injecting gas nozzle coöperating with said throat to inject a mixture of gas and induced air into the same 130

- and force the resulting explosive mixture through said diaphragm to burn within the surface layer thereof and maintain said coated granules in incandescent highly luminous condition, and an air chamber communicating with said cooling passages and with said throat to allow said injecting nozzle to draw air therethrough and cool the inner portions of said diaphragm.
- 10 3. In heating and lighting apparatus, a casing, a porous refractory diaphragm mounted in said casing and formed of united porous granules, the surface layer granules carrying rare earth actinic material to promote their luminosity, cooling passages through said diaphragm, a gas chamber formed in said casing and communicating with said diaphragm, an air chamber communicating with said cooling passages, and means for supplying to said gas chamber an explosive gaseous mixture of gas from a suitable source of supply and air from said air chamber under sufficient pressure to force the mixture through said diaphragm 25 to burn therein and to maintain said actinic granules in incandescent highly luminous condition, the air drawn from said air chamber being supplied through said cooling passages.
- 30 4. In heating apparatus, a casing, a porous refractory diaphragm supported by said casing and formed of united porous refractory granules, cooling passages through said diaphragm, a gas chamber formed in said casing and communicating with said diaphragm, injecting means comprising a throat and a gas nozzle coöperating to inject a mixture of gas and induced air into said casing and force the resulting explosive 35 mixture through said diaphragm to burn
- within the surface layer thereof, and an air chamber communicating with said cooling passages and with said throat to allow said injecting nozzle to draw air therethrough and cool the inner portions of said dia- 45 phragm.
5. In a heating apparatus, a casing, a porous refractory diaphragm supported by said casing, cooling passages through said diaphragm, a gas chamber formed in said casing and communicating with said cooling passages, and means for injecting into said gas chamber an explosive mixture of gas and of air drawn from said air chamber and to force said mixture through said diaphragm to burn within the surface layer thereof.
6. In heating apparatus, a casing, a porous refractory diaphragm supported by said casing, cooling passages through said diaphragm, a gas chamber formed in said casing and communicating with said diaphragm, and means to inject a mixture of gas and induced air into the same and force the resulting explosive mixture through said diaphragm to burn within the surface layer thereof.
7. Heating apparatus comprising a porous and permeable bed of refractory material 70 having cooling passages extending therethrough, and means for forcing into said bed an explosive mixture of gas and of air drawn through said cooling passages to cause said explosive mixture to burn within 75 said bed.
